(57) **CLAIM**

The ornamental design for a fruit fly trap, as shown and described.

DESCRIPTION

FIG. 1 is a first perspective view of a fruit fly trap showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the fruit fly trap thereof; and,

FIG. 10 is an enlarged view of the selected portion 10 in FIG. 1.

The broken lines shown in the drawings depict portions of the fruit fly trap that form no part of the claimed design.
